UNITED STATES PATENT OFFICE

GLENN H. SEELINGER, OF GREELEY, COLORADO

BEET TOPPING ATTACHMENT FOR BEET PULLERS

Application filed February 8, 1931. Serial No. 514,553.

This invention relates to a topping attachment for sugar beet lifting and pulling machines. The principal object of this invention is to provide a simple and highly efficient device which can be attached to the frame of the present type of beet lifters or pullers and which will efficiently and uniformly top the beets in advance of the pulling or lifting operation.

10 Another object of the invention is to so construct the device that the tops will be discharged to the sides of the row leaving the beets clearly exposed for piling.

15 A further object of the invention is to provide a topper of this character the operation of which will not be interfered with by the leaves and stalks of the beets.

20 A still further object of this invention is to provide an automatic adjustment in a device of this character which will raise and lower the cutting knife according to the depth or projection of the beet top above the ground level so that all beets will be uniformly topped regardless of their position in the 25 ground.

Other objects and advantages reside in the detail construction of the invention, which is designed for simplicity, economy, and efficiency. These will become more apparent 30 from the following description.

In the following detailed description of the invention reference is had to the accompanying drawing which forms a part hereof. Like numerals refer to like parts in all views of the 35 drawing and throughout the description.

In the drawing:

Fig. 1 illustrates in broken line a typical beet lifter or puller and in solid line the improved topping attachment.

40 Fig. 2 is a plan view of the topping attachment.

Fig. 3 is a front view of the blade portion of the attachment. This view is taken on the line 3—3, Fig. 1.

45 Fig. 4 is a detail view illustrating the construction of the guide roller employed in the device.

Fig. 5 is a detail view of the cutting blade, illustrating its position with reference to the 50 beet row.

The frame of a typical beet lifter or puller is indicated at 10 with its lifting blades at 11. Typical sugar beets are indicated at 12. The operation of the usual lifter or puller is well understood, the machine is simply drawn along the rows so that the lifting blades 11 will engage each side of the beets and lift them from the ground. The beets may be simply lifted and left protruding, or may be completely pulled and left lying along the row. This invention attaches to the frame 10 ahead of the blades 11 so that before the beets 12 are lifted or pulled the tops will be cut therefrom.

The invention comprises a pair of frame blocks 13 adapted to be clamped or otherwise secured to the frame 10 by means of suitable attachment bolts 14. The blocks 13 support a lateral shaft 15 across and above the frame 10. The shaft may be maintained in position by means of cotter pins 29 or similar devices.

A pair of arms 16 depend from and are hinged or pivoted upon the shaft 15. Spacing washers 30 are provided to properly position the arms on the shaft 15. The arms 16 are braced from each other and maintained in spaced relation by means of any suitable spacers or cross bracing 17. The arms 16 and the bracing 17 form what might be termed a roller frame. A V shaped, top-parting bar 28 extends forwardly from the arms 16.

A roller shaft 18 extends between the lower extremities of the arms 16 and provides a bearing shaft for a relatively heavy aligning roller 19. The aligning roller is journalled upon roller bearings 20 about the shaft 18. Suitable packing 21 and packing nuts 22 are provided to prevent the access of dirt and grit to bearings 20 and to maintain the grease or other lubricant therein. A central guide flange 23 surrounds the mid portion of the aligning roller 19.

A bracket member or bracket arm 24 is attached adjacent the upper portion of each arm 16, as shown at 25. The bracket members extend first rearwardly and outwardly, then are bent to extend forwardly and inwardly terminating in an attachment to a

95

100

V-shaped cutting blade 26. The bracket members 24 maintain the blade 26 in a substantially horizontal position and also provide support for a pair of curved, outwardly flared deflecting plates 27 which are attached thereto.

It will be noted from the above construction that the entire mechanism is free to swing rearwardly and upwardly about the 10 shaft 15 and that regardless of the swing the relative position between the cutting blade 26 and the aligning roller 19 is always maintained uniform.

In use, the parting bar 28 will act to part 15 or separate the leaves and stems of the beets to each side so as to allow the aligning roller 19 to enter therebetween and roll over the top of the beet. As before stated, the roller 19 is comparatively heavy. Its weight in addition to the weight of the attached members causes it to crush the leaves and stems down against the beet top so that it can accurately align the cutting knife therewith. Immediately after the roller 19 has rolled 20 upon one of the beets 12 the cutting blade 26 will enter the beet in spaced relation to the position of the roller 19 and sever the top therefrom. After the blade has entered the beet it will maintain its horizontal cutting 25 position until it has passed completely therethrough regardless of the fact that the roller 19 may have left the beet.

Should a low beet be encountered the aligning roller will drop and properly lower 30 the cutting blade. Should a high beet be encountered the roller will rise and raise the cutting blade so that all the beets will be uniformly topped regardless of their position. After the tops have been severed from 35 the beets they will be thrown to the side of the row by the plates 27.

It is desired to call attention to the peculiar design and positioning of the cutting 40 knife 26. This knife is formed of comparatively thin, tempered steel or similar material so that it will enter and pass through the beet without exerting a wedging action to break or tear the top therefrom. It is also 45 constructed in a V-shaped design with one leg of the V longer than the other leg, as illustrated more in detail in Fig. 5. The long leg is designed to do the majority of the cutting. It will be noted that the blade is so 50 positioned that the apex of the V comes toward one side of the center line of the beet row, indicated by the line A—A, Fig. 5. This allows the long leg to enter the beet 55 on a slant and be pushed through diagonally which greatly facilitates a smooth clean-cut without breakage and with a minimum of drag upon the machine. This also provides a greater bearing surface on the beet for the support of the topping structure 60 after the roller has left the top. The peripheral guide flange 23 is sharpened and en-

ters the beet top. It acts to accurately guide the knife through the beet and prevents either the beet or the knife from moving to one side.

While a specific form of the improvement 70 has been described and illustrated herein, it is desired to be understood that the same may be varied, within the scope of the appended claims, without departing from the spirit of the invention.

Having thus described the invention, what is claimed and desired secured by Letters Patent is:—

1. A topping attachment for a beet lifter of the type having a frame comprising: a 80 pair of blocks; means for attaching said blocks to said frame; a lateral shaft supported by said blocks across said frame; a roller frame swingingly mounted on said shaft and extending downwardly and rearwardly therefrom; a roller journaled in said roller frame; bracket arms secured adjacent the upper portion of said roller frame and curving to a position immediately in the rear of said roller; a blade extending between the 85 lower extremities of said bracket arms and positioned a predetermined distance below and at the rear of said roller.

2. A topping attachment for a beet lifter of the type having a frame comprising: a 90 pair of blocks; means for attaching said blocks to said frame; a lateral shaft supported by said blocks across said frame; a roller frame swingingly mounted on said shaft and extending downwardly and rearwardly therefrom; a roller journaled in said roller frame; bracket arms secured adjacent the upper portion of said roller frame and curving to a position immediately in the rear of said roller; a blade extending between the lower extremities of said bracket arms and positioned a predetermined distance below and to the rear of said roller; and a curved plate supported by each of said bracket arms, said 100 plates curving outwardly and upwardly from a position immediately in the rear of said blade so as to direct the severed tops to the side.

3. A blade for beet topping devices comprising: a relatively narrow, thin, V-shaped, 110 blade-like member adapted to be positioned with its apex forwardly and to one side of the center line of the beets to be topped, one leg of the V being relatively long, said latter leg adapted to cross said center line.

4. A topping attachment for the frame of a beet lifter comprising: a lateral shaft arranged to extend across said frame; means for supporting the extremities of said shaft from said frame; a pair of arms extending 120 downwardly and rearwardly from said shaft and arranged to pivot thereon; brace members arranged to maintain said arms in parallel, spaced relation; a roller shaft extending between the lower extremities of said arms; a 125

- roller mounted on said latter shaft; a bracket member secured adjacent the upper portion of each arm said bracket members extending first rearwardly, thence downwardly and forwardly so as to terminate below and at the rear of said roller and a relatively narrow V-shaped cutting blade extending forwardly from one of said members and returning rearwardly to the other member.
- 5 10 5. A topping attachment for the frame of a beet lifter comprising: a lateral shaft arranged to extend across said frame; means for supporting the extremities of said shaft from said frame; a pair of arms extending downwardly and rearwardly from said shaft and arranged to pivot thereon; brace members arranged to maintain said arms in parallel, spaced relation; a roller shaft extending between the lower extremities of said arms; a roller mounted on said latter shaft; a bracket member attached adjacent the upper portion of each arm, said bracket member extending first rearwardly and outwardly, thence forwardly and inwardly so as to terminate immediately in the rear of and below said roller and a relatively narrow, thin, V-shaped horizontally placed cutting blade extending between the extremities of said arms and forwardly therefrom to a position under said roller.
- 15 20 25 30 6. A topping attachment for the frame of a beet lifter comprising: a lateral shaft arranged to extend across said frame; means for supporting the extremities of said shaft from said frame; a pair of arms extending downwardly and rearwardly from said shaft and arranged to pivot thereon; brace members arranged to maintain said arms in parallel, spaced relation; a roller shaft extending between the lower extremities of said arms; a roller mounted on said latter shaft; a bracket member attached adjacent the upper portion of each arm, said bracket members extending first rearwardly and outwardly, thence forwardly and inwardly so as to terminate immediately in the rear of and below said roller and a relatively narrow, thin V-shaped horizontally placed cutting blade extending between the extremities of said arms and forwardly therefrom to a position under said roller; and a plate secured to each of said arms, said plates arranged to approach each other at a point immediately back of said cutting blade and inclined outwardly from each other.

In testimony whereof, I affix my signature.
GLENN H. SEELINGER.
